CLAIM

The ornamental design for a combined pen and electronic device, as shown and described.

DESCRIPTION

FIG. 1 is a bottom perspective view of a combined pen and electronic device showing my new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is an enlarged bottom perspective view of the portion encircled in FIG. 1; and,

FIG. 9 is an enlarged left-side elevation view of the portion encircled in FIG. 4.

The evenly spaced broken lines shown in the drawings illustrate portions of the electronic device that form no part of the claimed design.

The dot-dash broken lines shown in the drawings illustrate a boundary line that forms no part of the claimed design.

The dot-dot-dash broken lines shown in the drawings delineate portions of the claimed design in FIGS. 1 and 8 that are illustrated in enlarged views and form no part of the claimed design.
